INDUCTOR TUNING SYSTEM

Frederick N. Jacob, Chicago, Ill., assignor to
 Aladdin Industries, Incorporated, a corporation
 of Illinois

Application April 4, 1946, Serial No. 659,465

6 Claims. (Cl. 250—40)

1

This invention relates to an inductor tuning system in which the frequency of a tuned circuit is varied by an inductor having a movable magnetic core.

In the mass production of radio equipment where variable inductance devices are used in the tuned circuits of a multitude of like receivers it is customary to provide substantially identical coil and core combinations for any given type of circuit common to these receivers. Since the distributed capacitances of the coil and core combinations and the inherent capacitances of the corresponding circuits in any one of the multitude of like apparatuses in which these combinations are used are never the same, it is necessary with said prior arrangements to compensate for the slight variations in capacitance by providing a trimmer condenser across the coil core combination and upon connecting the unit in a circuit to adjust the initial frequency value of the circuit by means of the trimmer condensers when the core has attained a predetermined position relative to the coil. This procedure is costly and has the added element of a trimmer capacitor of questionable stability. The trimmer condenser is made unnecessary by the use of the present invention, in accordance with which both the main condenser and the trimmer condenser are replaced by a single, highly stable fixed condenser, and the initial resonant frequency of the circuit is adjusted by adjusting the initial position of the core from which the core is moved over the tuning range. This is made possible by the particular construction of the coil or core or the combination of both as with the new construction it is immaterial from which position the core movement begins since with this construction equal amounts of core movement always produce equal amounts of frequency change.

An object of the present invention is to devise a permeability tuning system in which all of the required capacity in a tuned circuit may be incorporated in a fixed capacitor of the type which is free from the effects of vibration and humidity and in addition has a predetermined characteristic under temperature changes. Such capacitors may be of the ceramic type or molded mica construction.

A further object of the invention is to devise a novel tuning inductor by which a circuit may be tuned over the same frequency range for the same extent of movement of the core but with different values of capacity connected in the circuit.

Another object is to devise an inductor tuning system in which equal displacements of the tun-

2

ing core throughout different portions of a given tuning range will produce the same ratio of frequency change.

Still another object of the invention is to devise a novel tuning inductor by which two or more tuning circuits including different capacity values may be tuned over the same range of frequency by the simultaneous movement of the cores of said tuning elements through the same range of movement.

Where a fixed amount of capacity is to be used in a tuned circuit, with no provision for adjustment of this element, adjusting means must be embodied in the tuning inductor for initially establishing the desired resonant frequency of the circuit. Such adjusting means must be adaptable to use in the manufacture of large quantities of radio frequency apparatus incorporating such circuit elements. I propose to use the relative movement of the core and coil, not only to tune the resonant circuit throughout a substantial range of frequencies, but also to establish conformity of this range with a predetermined frequency band.

In order to accomplish the desired result, the tuning inductor must be so designed that the circuit in which it is employed may be tuned over a given frequency range for the same core movement but with different values of capacity connected in the circuit. This means that the core must be capable of producing the same frequency change in the circuit for a given movement even though the core may start from different initial positions for different values of capacity included in the circuit. I have discovered that the desired result may be obtained if the tuning inductor is designed so that within the desired tuning range, equal movements of the core produce equal changes in the logarithmic value of the frequency of the circuit. In other words, the tuning inductor must be designed to vary the inductance in the circuit in a manner such that there will be a straight line relation between the core displacement from a given position and the logarithmic value of the resulting resonant frequency of the circuit over a range in excess of the desired tuning range. Stated in another way, equal movements of the core must produce the same percentage change in frequency throughout the desired tuning range.

The inductor must vary the effective inductance of the circuit in a manner to produce a constant ratio between the core displacement and the change in the logarithmic value of the circuit inductance. Where the effective inductance of the circuit is

provided entirely by the inductor, the inductor must be designed to provide a constant ratio between core displacement and the change in the logarithmic value of the inductance of the inductor.

The desired change in inductance value may be accomplished by a number of different arrangements. First, the tuning inductor may be provided with a core of uniform density and constant diameter throughout its length, and the winding pitch of the coil may be varied along the length of the coil to secure the desired variation in inductance. In a second arrangement the coil diameter is varied along the length of the coil while keeping the turn spacing constant, the core being of uniform density and constant diameter throughout its length. In a third arrangement the coil diameter and turn spacing is constant but the diameter of the core varies along the length thereof to produce the desired variation in inductance. In a fourth arrangement, the coil has a constant diameter and uniform turn spacing throughout its length, the core being of uniform diameter but of varying density along its length. It is obvious that other arrangements are possible involving various combinations of variable coil and core diameters, variable turn spacing and variable core density.

This application is in part a continuation of my copending application Serial No. 549,444, filed August 19, 1944 now abandoned.

Various forms of my invention are illustrated in the accompanying drawing in which:

Figure 1 is a diagrammatic showing of the preferred coil-core combination of the tuning inductor;

Figure 2 shows a series of curves illustrating the tuning characteristic of the arrangement of Figure 1 for different values of capacity;

Figure 3 is a series of curves showing the tuning characteristic of a straight line frequency tuning inductor for comparison with the arrangement of Figure 1;

Figure 4 is a diagrammatic showing of a second form of tuning inductor in which the diameter of the coil turns varies along the length of the coil;

Figure 5 is a series of curves illustrating the tuning characteristic of Figure 4;

Figure 6 is a diagrammatic showing of a third form of tuning inductor in which the diameter of the magnetic core varies along the length thereof;

Figure 7 is a series of curves showing the tuning characteristic of Figure 6;

Figure 8 is a diagrammatic showing of a fourth form of inductor in which the density of the magnetic core varies along the length thereof;

Figure 9 is a series of curves showing the tuning characteristic of the inductor of Figure 8;

Figure 10 is a rear elevational view of a tuning arrangement for simultaneously varying two inductors;

Figure 11 is a front view of the arrangement shown in Figure 10;

Figure 12 is a side view of Figure 10 with the near half of casing L cut away and

Figure 13 is a view of Figure 10 from below that figure.

The desired tuning characteristic for a resonant circuit including the tuning inductor is shown by curve 1 of Figure 2, where the movement of the core is plotted in inches on a linear scale as measured from an initial position at which the circuit is tuned to two megacycles. As the core

moves into the coil, the resonant frequency of the tuned circuit decreases and the resonant frequencies at different positions of the core are plotted on a logarithmic scale. As will be seen, the curve 1 is essentially a straight line between frequency limits of 1.9 to 1.0 megacycles. The inductor represented by curve 1 will be suitable for tuning over a band extending from 1.2 to 1.8 megacycles.

An inductor for producing a characteristic like curve 1 of Figure 2 is diagrammatically shown in Figure 1. The cylindrical coil form 5 has an inside diameter of 0.52 inch and an outside diameter of 0.57 inch. The winding 6 consists of 22.35 turns of No. 30 plain enameled wire wound within the space of 1 $\frac{1}{8}$ inches. As shown in the drawing, the coil is divided into six sections of different lengths and each section has a different turn spacing or winding pitch. Beginning with section 1 adjacent the core end of the coil, the following table gives the winding pitch, the number of turns in each section and the length of each section:

25	Section	Turns per inch	Turns	Length
1		19	2.4	.1265
2		14	2.7	.193
3		12	4.2	.350
4		15.5	5.7	.368
5		22.5	3.35	.149
6		32	4.00	.125
			22.35	1.3115

35 The core 7 of Figure 1 is a compressed hollow core formed of No. 521 Aladdin ferromagnetic material and having an inside diameter of 0.200 inch, an outside diameter of 0.500 inch and a length of 1.5 inches.

40 Curve 1 of Figure 2 represents the tuning characteristic of the inductor of Figure 1 where the capacitor connected to the coil has a capacity value of 1930 mmfd. (micromicrofarads). Curves 2, 3 and 4 represent the tuning characteristic of Figure 1 where the capacitor has smaller capacity values of 1830, 1730 and 1630 micromicrofarads, respectively. It is to be understood that values somewhat larger could have been used as well.

45 If a capacity C is required to give the characteristic as shown by curve 1 in Figure 2 for a tuning range extending from 1.2 to 1.8 mc., then essentially the same curve may be obtained over the same frequency range by using a capacity as small as:

$$C_{\min} = \left(\frac{1.0}{1.2}\right)^2 C$$

or by using a capacity as large as:

$$C_{\max} = \left(\frac{1.9}{1.8}\right)^2 C$$

50 In order to use capacitors of different values it is merely necessary to shift the initial position of the core with respect to the coil, and all other frequencies would occur at the same position of core displacement with respect to the starting point, provided the value of the tuning capacity falls between the above indicated limiting values.

55 From Figure 2 it can be seen that the effect of using capacitors of different values is to displace the curve horizontally. All four curves are substantially parallel to one another, and the same net core displacement from the initial position at 75 one limit of the tuning band, produces the same

change in frequency in each case. It may also be noted that the family of curves shown in Figure 2 provides the same ratio of frequency change for a given core displacement for all curves or for any portion of any curve lying within the useful tuning range.

In Figure 2, the portion of curve 1 between the frequency limits of 1.9 to 1.0 mc. may be considered to be a straight line. This relationship may be expressed by the following equation.

$$\log f = K(P - P_0) + \log f_0 \quad (1)$$

where

f is the frequency tuned to

P is the corresponding core position on the scale of movement

K is the slope of the curve and is a constant

f_0 is the upper limit of frequency for the straight line relationship; in this case 1.9 mc.

P_0 is the corresponding core position for frequency f_0

This Equation (1) may be restated

$$P = \frac{1}{K} \log \frac{f}{f_0} + P_0 \quad (2)$$

If only a portion of the curve is considered, bounded by end frequencies f_1 and f_2 , for example 1.8 mc. and 1.2 mc., the equations for the limits of this range may be written

$$P_1 = \frac{1}{K} \log \frac{f_1}{f_0} + P_0 \quad (3)$$

$$P_2 = \frac{1}{K} \log \frac{f_2}{f_0} + P_0 \quad (4)$$

which shows that for any frequency f_1 , there is a corresponding core position P_1 , and for any frequency f_2 , there is a corresponding position P_2 . In tuning from frequency f_1 to frequency f_2 , the core displacement will be the difference in the positions P_1 and P_2 , viz:

$$P_1 - P_2 = \frac{1}{K} (\log f_1 - \log f_2) \quad (5)$$

If new circuit constants are assumed (in this case a different value of circuit capacitance), it remains to determine the core displacement necessary to tune again from frequency f_1 to frequency f_2 . Since

$$f = \frac{1}{2\sqrt{LC}} \quad (6)$$

where

L is the value of inductance provided by core position P and

C is the circuit capacitance

the relationship between core position and circuit inductance may be given as

$$P = \frac{1}{K} \log \frac{1}{2\pi f_0 \sqrt{LC}} + P_0 \quad (7)$$

Thus, for any position P_1 , there is a corresponding inductance L_1 , and for any position P_2 , there is an inductance provided which may be termed L_2 .

$$P_1 = \frac{1}{K} \log \frac{1}{2\pi f_0 \sqrt{L_1 C}} + P_0 \quad (8)$$

$$P_2 = \frac{1}{K} \log \frac{1}{2\pi f_0 \sqrt{L_2 C}} + P_0 \quad (9)$$

But if a somewhat different value of capacitance, C' , is now assumed, in place of C , whose value falls within the limits established above, then if Equation 6 is considered, and the value

C' is substituted for capacitance C , then to tune to the same frequency f , a new value of inductance must be found to satisfy Equation 6, and it can be expressed as

$$L' = \frac{C}{C'} L \quad (10)$$

That is to say, for any frequency considered, if the circuit capacitance is changed to C' , then the core must be moved to a new position which provides a value of inductance which has been modified by the factor

$$\frac{C}{C'}$$

We may write

$$P'_1 = \frac{1}{K} \log \frac{1}{2\pi f_0 \sqrt{L'_1 C}} + P_0 \quad (11)$$

$$P'_2 = \frac{1}{K} \log \frac{1}{2\pi f_0 \sqrt{L'_2 C}} + P_0 \quad (12)$$

but

$$L'_1 = \frac{C}{C'} L_1 \quad (13)$$

$$L'_2 = \frac{C}{C'} L_2 \quad (14)$$

Simplifying

$$P'_1 = P_1 - \frac{1}{K} \log \sqrt{\frac{C}{C'}} \quad (15)$$

$$P'_2 = P_2 - \frac{1}{K} \log \sqrt{\frac{C}{C'}} \quad (16)$$

the net core displacement is the difference between the new core positions, or,

$$P'_1 - P'_2 = P_1 - P_2 \quad (17)$$

Equation 17 indicates that under the conditions previously set up, a given frequency range may always be covered, when using different tuning capacities, by equal core movements. Likewise, since f_2 need not necessarily be the end frequency on the band, but can be any frequency in the band, the core movement needed to tune from the end frequency f_1 to this other frequency f_2 falling anywhere in the band will always be the same, and an identical curve shape will result from that secured using the original set of circuit constants, but displaced horizontally from the original.

By taking Equation 5 a step further, we have

$$P_1 - P_2 = \frac{1}{K} \log \frac{f_1}{f_2} \quad (18)$$

For any other pair of frequencies, f_3 and f_4 , satisfying the relationship

$$\frac{f_3}{f_4} = \frac{f_1}{f_2} \quad (19)$$

the corresponding core displacement always equals P_1 minus P_2 . Stated another way, under this system, for any frequency band having a given ratio of frequency coverage, an identical core displacement is required.

The distinction between the system of this invention and a straight line frequency system will now be shown. Curve 3a of Figure 3 shows the tuning characteristic provided by a core and coil similar to the ones considered above, but designed so as to offer an essentially linear relationship between core movement and frequency of the oscillatory circuit of which the combination forms a part. It will be observed that the

scale used for both frequency and movement is linear. As for the curve trace itself, it is substantially a straight line between the frequency limits of 1.9 mc. to 1.05 mc. If, for example, it has been decided that the portion of the curve to be used shall be a straight line between the frequency limits of 1.8 to 1.2 mc., then the tuning capacitance C used in obtaining the curve 3a of Figure 3 may be increased to a limit of

$$C_{\max} = \left(\frac{1.9}{1.8}\right)^2 C$$

or it may be decreased to a limiting value of

$$C_{\min} = \left(\frac{1.05}{1.2}\right)^2 C$$

Under any value of C falling within these limits, this core and coil combination when used in the same oscillator arrangement will provide a linear relationship between frequency and core movement, for a frequency band of 1.8 to 1.2 mc. The four curves shown in Figure 3 correspond to four values of C, all lying within the above indicated range. While they are all substantially straight lines, they all have different slopes. That is to say, the frequency range covered for a given core movement varies depending on the capacitance used in the circuit.

Because the core and coil characteristics used in securing the relationships shown in Figure 2 may be substantially different from those used to provide the curves of Figure 3, it is to be understood that where the symbols C, L, f, etc. appear in the mathematical analysis of Figure 3, they are not to be confused with like symbols used in the foregoing discussion of the curves of Figure 2.

To state the mathematical relationship of the curves of Figure 3, the portion of the curve 3a extending from 1.9 mc. to 1.05 mc., may be considered to be a straight line and may be expressed by the following equation:

$$f = K(P - P_0) + f_0 \quad (20)$$

where

f is the frequency tuned to

P is the corresponding core position on the scale of core movement

K is the slope of the curve and is a constant

f_0 is the upper limit of frequency for the straight line relationship, i. e., 1.9 mc.

P_0 is the core position corresponding to f_0

This Equation 20 may be rewritten

$$P = \frac{1}{K}(f - f_0) + P_0 \quad (21)$$

Now, if only a portion of this curve is considered, bounded by end frequencies f_1 and f_2 , for example 1.8 mc. and 1.2 mc., the equation for these limiting frequencies may be stated

$$P_1 = \frac{1}{K}(f_1 - f_0) + P_0 \quad (22)$$

$$P_2 = \frac{1}{K}(f_2 - f_0) + P_0 \quad (23)$$

In tuning from frequency f_1 to frequency f_2 , the core movement will be the difference in the positions P_1 and P_2 , viz.:

$$P_1 - P_2 = \frac{1}{K}(f_1 - f_2) \quad (24)$$

If a new value of circuit capacitance is now assumed it remains to determine the core displacement required to tune again from frequency f_1 to frequency f_2 . By resorting to Equation 6,

we can establish the relation between core position and circuit inductance, thus:

$$P = \frac{1}{K} \left(\frac{1}{2\pi\sqrt{L}C} - f_0 \right) + P_0 \quad (25)$$

For any position P_1 there is a corresponding inductance L_1 and for any other position P_2 , there is an inductance L_2 .

$$P_1 = \frac{1}{K} \left(\frac{1}{2\pi\sqrt{L_1}C} - f_0 \right) + P_0 \quad (26)$$

$$P_2 = \frac{1}{K} \left(\frac{1}{2\pi\sqrt{L_2}C} - f_0 \right) + P_0 \quad (27)$$

Using a new value of capacitance C' , in place of C, whose value falls within the limits established above, to tune to the same frequencies f_1 and f_2 we must modify the value of inductance by the factor

$$L' = \frac{C}{C'} L \quad (10)$$

The core positions corresponding to these new inductances are

$$P'_1 = \frac{1}{K} \left(\frac{1}{2\pi\sqrt{L'_1}C'} - f_0 \right) + P_0 \quad (28)$$

$$P'_2 = \frac{1}{K} \left(\frac{1}{2\pi\sqrt{L'_2}C'} - f_0 \right) + P_0 \quad (29)$$

but

$$L'_1 = \frac{C}{C'} L_1$$

and

$$L'_2 = \frac{C}{C'} L_2$$

Simplifying Equations 28 and 29 provides

$$P'_1 = \sqrt{\frac{C}{C'}} P_1 - \left(1 - \sqrt{\frac{C}{C'}}\right) \left(\frac{f_0}{K} - P_0\right) \quad (30)$$

$$P'_2 = \sqrt{\frac{C}{C'}} P_2 - \left(1 - \sqrt{\frac{C}{C'}}\right) \left(\frac{f_0}{K} - P_0\right) \quad (31)$$

the net displacement is difference between positions P'_1 and P'_2 , viz.:

$$P'_1 - P'_2 = \sqrt{\frac{C}{C'}} (P_1 - P_2) \quad (32)$$

Equation 32 indicates that the use of a new value of circuit capacitance, C' , in place of the original capacity C, requires a change in core displacement by a factor

$$\sqrt{\frac{C}{C'}}$$

Under these conditions it would be impossible to maintain the same frequency calibration for different values of capacity by using displacement trimming, that is to say, by operating over a different portion of the inductance-movement curve.

Curves 3a and 3f of Figure 3 illustrate the change in the slope of the frequency/movement characteristic with different values of capacitance, provided by the two systems, when employing coils of approximately the same configuration. Except for the error introduced by the non-conformity of the coils to the ideal or perfect shape, the logarithmic arrangement results in a substantially constant slope as shown by curve 3a while the straight line frequency arrangement has a very definitely varying slope as shown by curve 3f. These two curves are plotted on an

abscissa scale of capacity units of micromicrofarads and an ordinate scale in units of megacycle coverage per inch of core travel.

The physical dimensions of the coil and core combination for curve 3e has already been given above. For curve 3f, the same core was used, but the coil had a different winding pattern to secure the straight line frequency characteristic. The coil form had an inside diameter of 0.52 inch and an outside diameter of 0.57 inch. The winding was $1\frac{1}{8}$ inches long and consisted of 22.3 turns of No. 30 P. E. wire wound in six sections as follows:

Section	Turns per inch	Turns	Length
1	19	2.4	.126
2	12.5	2.4	.192
3	10	1.7	.170
4	11	2.0	.182
5	16	5.9	.369
6	20	7.9	.272
		22.3	1.311

Instead of varying the pitch of the winding turns along the length of the winding, the desired variation in inductance may be obtained by varying the diameter of the turns in different sections of the winding. Such an arrangement is shown in Figure 4 where the pitch of the winding is constant throughout the length thereof but the diameter of the turns varies in different linear sections. The curves shown in Figure 5 illustrate the tuning characteristic of an inductor designed with a variable turn diameter and illustrated in Figure 4. It will be understood that the following example is for the purpose of illustration and not by way of limitation.

The core 7 of Figure 4 is the same as the core for Figure 1. The coil form 5a has a cylindrical inner bore of 0.505 inch diameter throughout the length, but the outside diameter of different linear sections of the coil form varies in accordance with the following table:

Section	Length	Outside Diameter
	Inches	Inches
1	.140	.700
2	.160	.600
3	.450	.750
4	.250	.550
5	.343	.535

The winding of Figure 4 is formed of No. 30 P. E. wire and consists of 21.5 turns wound at a pitch of 16 turns per inch, the total winding length being $1\frac{1}{8}$ inches. With the core positioned so the end thereof is $\frac{1}{2}$ of an inch removed from section 1 of the winding, the resonance frequency of the circuit was 2 megacycles with a capacity C of 1910 mmfd. As shown by the curve 5A of Figure 5, the tuning characteristic of the inductor is a straight line from 1.9 mc. to 1.1 mc. For an effective tuning range having upper and lower limits of 1.8 and 1.2 mc., curves 5B and 5C show the tuning characteristics for the limiting conditions where the tuning capacities are 1720 mmfd. and 2080 mmfd. As will be seen from Figure 5, all three curves are straight lines between the limits of 1.2 to 1.8 megacycles and are parallel to each other.

In a third modification the desired inductance variation is secured by a special core construction in which the diameter of the core varies in

different linear sections thereof. One specific example of core design will be given by way of illustration. This arrangement is illustrated in Figure 6 and the tuning characteristics are shown in Figure 7.

The coil for the inductor of Figure 6 is wound of No. 30 P. E. wire at a pitch of 19 turns per inch and includes a total of 25 turns. The coil form has an outside diameter of 0.535 inch and an inside diameter of 0.505 inch. Capacitor C for curve 7A had a value of 1940 mmfd.

The core 7a of Figure 6 is built up of six sections #1 to #6, each $\frac{1}{4}$ inch in length but varying in outside diameter. The core sections are assembled on an insulating rod 7b of 0.187 inch diameter passing through a center hole common to all of the sections. Beginning with the section adjacent the tuning coil as No. 1, the outside diameters of the core sections are 0.42 inch, 0.44 inch, 0.47 inch, 0.5 inch, 0.5 inch, 0.49 inch. All of the core sections are formed of compressed ferromagnetic material (Aladdin No. 521) having a density of approximately 5 gr./cc. It will be understood that the core may be formed as a single compressed body instead of being assembled in sections.

Curve 7A in Figure 7 illustrates the tuning characteristic of the inductor of Figures 6 where the capacity C has a value 1940 mmfd. This curve is substantially straight from 1.85 mc. to 1.15 mc. If the effective tuning range is to extend from 1.8 mc. to 1.2 mc., then the values of capacity C will be 1785 mmfd. for curve 7B and 1990 mmfd. for curve 7C. All three curves are essentially parallel and straight from 1.8 mc. to 1.2 mc.

The various core sections of Figure 6 may all have the same external diameter but different sizes of central openings so as to secure the necessary variation in cross-sectional area of the core along the length thereof.

Figure 8 illustrates another arrangement for securing the desired variation in inductance in which the winding pitch and turn diameter of the coil are constant throughout its length, and the inside and outside diameters of the core are constant, but the density of different linear sections of the core varies. One specific example of construction will be described by way of illustration for producing a tuning characteristic according to Figure 9. In the construction diagrammatically illustrated in Figure 8, the coil consists of 22.5 turns of No. 30 P. E. wire uniformly wound over a length of $1\frac{1}{8}$ inches on a cylindrical coil form having an outside diameter of 0.607 inch and an inside diameter of 0.505. The core 7a is formed of four sections mounted on an insulating rod 7b which passes through a central hole common to all of the sections. The different sections of the core are formed of compressed ferromagnetic material (Aladdin No. 521) and of varying lengths and density according to the following table:

Section	Length	Density
	Inches	
1	$\frac{3}{8}$	4.02
2	$\frac{1}{4}$	3.39
3	$\frac{1}{4}$	5.60
4	$\frac{5}{8}$	5.65

It will be understood that the core may be formed as a single composed body instead of being assembled in sections.

Curve 9A of Figure 9 shows the tuning characteristic of the inductor of Figure 8 where the circuit has a frequency of 2 mc. when the end of section 1 of the core is positioned $\frac{1}{2}$ of an inch from the end of the coil 6 and with a value of condenser C of 1900 mmfd. This curve is essentially straight over the range extending from 1.9 mc. to 1.2 mc. For a tuning range varying from 1.8 mc. to 1.2 mc., one limiting value of condenser C will be 2115 mmfd. which results in a characteristic according to curve 9C, and the other limiting value of condenser C will be 1900 mmfd. which produces a tuning characteristic according to curve 9A. Curve 9B illustrates the characteristic obtained by using an intermediate value of C=2000 mmfd. Again the three curves are substantially parallel to one another.

While the four specific examples given above involve a coil and core combination for use over the range of 1.8 to 1.2 megacycles, which represents a frequency ratio of 1.5 to 1, it will be understood that the same principles can be applied for covering a tuning range having a frequency ratio as great as 3 to 1.

In the arrangements represented in Figures 1, 4, 6 and 8 the condenser C is connected directly across the inductor coil, and the effective inductance of the tuned circuit is provided entirely by the variable inductor. It will be understood, however, that the principles of my invention may be applied to a circuit in which a part of the circuit inductance may be embodied in a separate inductor connected in series with the condenser and the tuning inductor.

Where all of the circuit inductance is provided by the variable inductor, the design for the inductor must satisfy Equations 7, 8 and 9 above. The relation between the distance D of travel of the core between positions P1 and P2 and the circuit constants may be obtained by subtracting Equation 9 from Equation 8 which results in

$$D = \frac{1}{K} \left(\log \frac{1}{\sqrt{L_1}} - \log \frac{1}{\sqrt{L_2}} \right)$$

Transposing and further simplifying, this equation becomes

$$\log_{10} L_1 - \log_{10} L_2 = aD \quad (33)$$

Equation 33 requires a constant ratio between the change in core position and the change in the logarithmic value of the inductance of the inductor. In other words, the difference between the logarithms of the inductance values L1 and L2 at two different positions P1 and P2 of the core is proportional to the distance D between the two positions. Stated more simply, the curve of logarithmic value of inductance against core position is a straight line having a constant slope. Also, the curve showing the logarithm of the reciprocal of the inductance against core position is a straight line having a constant slope but in the opposite direction.

Where some of the circuit inductance is embodied in a separate inductor having a value of La, the design of the variable inductor must still satisfy Equations 7, 8 and 9 above, but the expressions $\sqrt{LC}$, $\sqrt{L_1C}$ and $\sqrt{L_2C}$ in these equations would assume the form of $\sqrt{(La+L)C}$, $\sqrt{(La+L_1)C}$ and $\sqrt{(La+L_2)C}$ respectively. In this case, the equation for the variable inductor, corresponding to Equation 33 above, would be

$$\log_{10}(L_1+La) - \log_{10}(L_2+La) = aD$$

For all of the arrangements described above

it will be understood that more than one winding layer may be used if desired. Also, the desired turn density along the length of the coil may be secured by first winding a layer of turns of constant pitch and then winding additional turns on top of this layer and distributed along the length of the winding space to secure the desired turn distribution.

It is obvious that my invention is not limited to the use of cores formed of compressed, finely-divided ferromagnetic material but cores of the laminated type may be employed.

A permeability tuning combination of coil and movable core may be so designed as to exhibit substantially the same temperature coefficient for any position of the core with respect to the coil. By temperature coefficient is meant the rate at which the inductance of the combination device changes with unit change in temperature. This combination likewise may be treated to make it relatively immune from the effect of high degrees of humidity to which it may be subject. It is inherently resistant to vibration. Through the use of a fixed capacitor, matching these properties (having a compensating temperature coefficient), an exceedingly stable tuned circuit may be evolved, and through proper design a vacuum tube oscillator incorporating such a tank circuit may be made which approaches the stability of crystal controlled oscillator systems.

While mention has been made of a relatively restricted band of frequencies, i. e., 1.8 to 1.2 mc., it is to be understood that the same principles may be employed in radio apparatus having more than one oscillatory circuit, as for instance, in the radio frequency stages of a tuned radio frequency receiver or a superheterodyne receiver, operating over more extended ranges. In the latter case the local oscillator circuit will follow a semi-logarithmic straight line relationship of frequency vs. movement as disclosed above. The other preselector stages will also have such a characteristic, but since they operate over a frequency band which is usually lower than that of the local oscillator frequency spectrum by an amount equal to the intermediate frequency, some amount of misalignment will result between the circuits, although the resultant attenuation will not be severe.

These principles may also be advantageously employed in the master oscillator and succeeding amplifier stages of radio frequency transmitters. Here, the cumbersome and costly air dielectric capacitors could be dispensed with, thus saving space and improving reliability. In the master oscillator, the use of my system improves frequency stability.

In various applications of my invention, it is necessary to operate two or more inductors from a common actuating member, and the operating means for each inductor should include provision for varying the initial setting of the core with respect to the coil. One suitable arrangement for simultaneously operating the cores of two inductors which may be included in separate tuning circuits is illustrated in Figures 10 to 13, inclusive, but it will be understood that other arrangements are possible.

Referring to Figure 10, two substantially identical inductor units having coils Aa and Ab and movable cores Ba and Bb are connected in separate tunable circuits including condensers Ca and Cb which may have different values. The coils of the two inductors are carried by brackets Da and Db which in turn are mounted for

vertical adjustment on a supporting panel E. Each of these brackets is provided with rack teeth on one edge thereof by which the bracket may be adjusted in a vertical direction by means of a suitable pinion tool, as will be more clearly understood from the patent to Schaper 2,272,433. The cores Ba and Bb are supported from a horizontal cross-arm F by means of a pair of threaded rods or stems Fa and Fb having threaded engagement with cross-arm F which in turn is mounted upon vertical slide Fc. Any suitable means may be employed for operating slide Fc to move the cores in and out of the coils, such as a rack and pinion arrangement, or an arrangement may be employed like that disclosed in the patent to Kirk et al. 2,286,283. This arrangement involves a tuning spindle G which drives a pulley H through a string K, and the pulley H operates a suitable mechanism to produce rectilinear motion of slide Fc. A horizontal frame or panel L is mounted on panel E and carries a frequency scale La. A movable frequency pointer or indicator Lb is supported from the top edge of the panel L and is adjustably clamped to an operating string Le mounted directly behind the panel L and extending parallel to the upper edge of the panel L. The string Le passes around suitable guiding pulleys and is driven from a driving pulley Ld mounted on the shaft of a pinion Fd having engagement with rack teeth formed on one edge of slide Fc. Thus, vertical movement of slide Fc is translated into horizontal movement of pointer Lb and there is a fixed linear relationship between the movement of the pointer and the movement of the inductor cores.

The tuner just described provides three adjustments, namely, (1) the pointer Lb is adjustable along string Le and may be clamped in any desired position; (2) each core may be adjusted with respect to its associated coil or with respect to the other cores by means of the threaded stem support for the core; and (3) each coil may be adjusted with respect to its associated core or with respect to the other coils by vertical adjustment of the mounting bracket.

Where the two circuits including capacitors Ca and Cb are to be tuned over the same frequency range, and the two capacitors have the same value, the two cores will have the same initial setting with respect to the associated coils. The tuner is then operated until the circuits are tuned to a known frequency within the desired range, and the pointer is then adjusted to indicate the correct frequency. It is obvious that each core-coil combination may be adjusted to the same relative setting by adjustment of either the core or the coil.

In case one of the capacitors has a different value of capacity, the two inductors will require different relative settings, and the proper setting of each inductor may be made by adjustment of either the coil or the core. Even though the two inductors have different settings, and the two capacitors are of different values, the tuning of the two circuits will track over the same range provided the two capacities are within the maximum and minimum values as explained above. Accordingly, my invention makes it possible to use fixed capacitors in gang-tuned circuits, and the capacitors may have different capacity values without the necessity of providing additional tuning elements for trimmer adjustment.

I claim:

1. A tuning system comprising a pair of tuned

circuits having different capacitance values, each circuit including a variable inductor comprising a coil and a relatively movable magnetic core for varying the inductance of said coil, said variable inductors being substantially identical, and the coil of each inductor having inductance determining structure so related to the inductance determining structure of its associated core that equal movements of said core over different portions of the range of tuning movement produces equal changes in the logarithmic value of the effective inductance of said circuit, a movable operating member, and means connecting said cores for movement in unison by said operating member, one of said cores being relatively displaced with respect to the other to tune said circuits to the same frequency.

2. In a tuning system, the combination of a variable inductor comprising a coil element having a movable magnetic core element for varying the inductance of said coil, and a condenser connected to said coil to form a resonant circuit, the elements of said variable inductor having inductance determining structure distributed along the lengths thereof to translate equal movements of said core into equal changes in the logarithmic value of the resonant frequency of said circuit.

3. In a tuning system formed of capacitance and inductance included in a closed resonant circuit, a device for varying the tuning of said circuit comprising a coil forming at least part of said inductance, and a movable magnetic core for said coil, the inductance controlling structure of said coil and core elements being so distributed along the lengths of said elements as to provide, over a substantial range of movement of said core, a constant ratio between the core displacement and the change in the logarithmic value of the effective inductance of said closed resonant circuit resulting from said displacement.

4. A two-part variable inductor comprising a coil and a relatively movable magnetic core therefor, said parts being formed of inductance determining structure distributed along the lengths thereof to produce, over a substantial range of movement of said core relative to said coil, a constant ratio between the relative displacement between said parts and the change in logarithmic value of the resulting inductance of said coil.

5. A variable inductor comprising an elongated coil part and an elongated magnetic core part, one of said parts being mounted for movement relative to the other part to vary the inductance of said coil, said parts being formed of inductance determining structure distributed along the lengths thereof to produce, over a substantial range of movement of said movable part, equal changes in the logarithmic value of the inductance of said coil for equal steps of movement of said movable part over different sections of said range.

6. In a tuning system formed of capacitance and inductance included in a closed resonant circuit, a device for varying the tuning of said circuit comprising a coil element forming at least a part of said inductance, and a magnetic core element for said coil, one of said elements being movable with respect to the other element for varying the inductance of said coil, said coil and core elements having inductance determining structure distributed along the lengths thereof to vary the resonant frequency of said closed circuit in accordance with a straight line graph of the loga-

75

rithm of the resonant frequency of the circuit plotted against the extent of relative movement between said elements from a predetermined position.
